SECTIONAL CHIP BREAKER

James S. Ballantine, Absecon, N. J.

Application May 17, 1949, Serial No. 93,702

5 Claims. (Cl. 144—244)

1

The present invention relates to sectional chip breakers for wood planing machines and the like and aims generally to improve the construction and operation of devices of this type.

A primary object of the invention is the provision of a sectional chip breaker of improved construction and operation for planing machines wherein the possibility of fragments of wood such as chips and the like becoming lodged into the working parts of the machine to disrupt operation thereof is substantially minimized and wherein means are provided for automatically comminuting chips or the like which may accidentally lodge in certain parts of the machine subject to be adversely affected thereby.

A further object of the invention is the provision of a sectional chip breaker of novel and simple construction in which parts of the device likely to be adversely affected by chips and the like are partly enclosed and shielded from flying chips.

A still further object of the invention is the provision of a sectional chip breaker of improved construction wherein the weight of the device and its pivotal mounting insures intimate contact of the chip breakers with the material being processed and wherein the chip breakers are mounted for individual and/or collective yielding movement in response to the surface characteristics of the material being processed.

Another object of the invention is the provision of a sectional chip breaker in which chips or fragments of wood which accidentally penetrate into certain parts of the machine likely to be damaged or obstructed thereby are automatically comminuted to thus eliminate the possibility of such damage or obstruction.

These and other objects and advantages of the invention will be apparent from a consideration of the accompanying drawings and appended specification which illustrate and describe a preferred embodiment of the invention.

In the drawings:

Fig. 1 is a plan view showing portions of a planing machine with my improved chip breaker attached thereto;

Fig. 2 is a plan view of the chip breaker;

Fig. 3 is a front elevational view of the chip breaker as viewed from the bottom in Fig. 2;

Fig. 4 is a vertical cross-sectional view of the chip breaker taken on the line 4—4 of Fig. 1;

Fig. 5 is a plan view of the cutter ring;

Fig. 6 is a vertical cross-sectional view of the cutter ring taken on the line 6—6 of Fig. 5;

Fig. 7 is a vertical cross-sectional view similar to Fig. 6 of a modified form of cutter ring; and,

Fig. 8 is a vertical cross-sectional view similar to Fig. 6 of a further modified form of cutter ring.

2

In accordance with the present invention the improved chip breaker device 10 comprises a plurality of individual presser feet 11 adapted to rest on a plank or the like between the cutter head 12 and the infeed roll 13 of a planer. The presser feet 11 are shaped to guide the wood chips upwardly instead of allowing them to fly outwardly along the plane of the incoming plank and are individually mounted on a guide bar 14 of vertically elongated rectangular cross-section for limited vertical movement to accommodate local variations in thickness of the material, such as a plank, being planed. Additional vertical movement of the presser feet is provided for by a pivotal construction comprising arms 15 and 16 secured to the ends of the guide bar 14 and pivotally mounted on the pivot pins 17 and 18 secured in the side frame members 19 and 20 of the planer. Thus smaller variations in thickness of the material being cut are automatically accommodated by the vertical movement of the individual presser feet while larger variations in thickness are accommodated by the clockwise pivoting of the chip breaker 10 about the pivot pins 17 and 18.

Downward movement of the presser feet 11 is limited by an adjustable stop device comprising adjustable screws 21 and 22 screw-threadedly carried by projecting arms 23 and 24 of the guide bar 14 and adapted to engage projecting stops 25 and 26 secured to the side frame members 19 and 20. For normal operation the adjustable stop device is adjusted so that the lower board contacting surfaces of the presser feet 11 are positioned somewhat below, for example, one-sixteenth of an inch below the lowest portion of the cutting circle of the cutter head 12.

The presser feet 11 comprise a body portion 27 and a foot portion 28. The foot portion 28 extends downwardly and rearwardly from the body portion 27 and has a lower board-engaging surface 29 and an upper curved chip guiding surface 30. The curved chip guiding surface 30 forms a continuation of the rearwardly inclined surface 31 of the body portion 27 and serves in conjunction therewith to guide and direct the chips upwardly in the machine.

As pointed out hereinbefore the presser feet 11 are individually mounted on the guide bar 14 of vertically elongated rectangular cross-section for limited vertical movement in response to local variations in thickness of a board being cut. For this purpose the rear side of the body portion 27 opposite the rearwardly inclined chip guiding surface 31 is cut out to form a U-shaped rectangular recess or opening 32 and upper and lower projecting flanged portions or walls 33 and 34. The recess 32 is shaped to house the guide bar 14 and is somewhat longer in its vertical dimension than

the vertical thickness thereof to permit the desired limited vertical movement of the chip breaker thereon. The inner wall of the recess forms a bearing surface having sliding engagement with one side of the guide bar. The presser feet are held in position on the guide bar 14 by bolts 35 which pass through aligned vertical bores 36 and 37 in the flanges 33 and guide bar 14 respectively and are screw-threadedly engaged with threaded vertical bores 38 in the flanges 34 10 aligned with the aforesaid bores. Springs 39 surround the lower ends of the bolts 35 and have one end thereof seating against the upper ends of the enlarged counterbores 40 in the lower portion of the guide bar 14 and the other end thereof seating against the flange 34 of the body portion 27. The upper portions of the springs are housed within the counterbores. In the construction shown the bolts 35 are freely slidable in the openings 37 of the guide bar 14 so that the presser feet 11 can at all times move upwardly against the action of springs 39 in response to unevenness in the material being cut.

As will be apparent from the description thus far, the mounting of the presser feet 11 is so arranged that the elements thereof which are likely to be clogged and/or obstructed by chips, sawdust, and the like are substantially shielded from the path of movement of such chips and the like so that clogging is reduced to a minimum. However, in the absence of complete enclosure, particles may sometimes seep into the working parts and prevent proper functioning of the device. This is particularly true in the case of particles, chips, and the like which may lodge between the lower surface of the upper flanges 33 and the upper surface of the guide bar 14 since the presence of such particles prevents proper seating of the presser feet with consequent inefficiency of operation.

In accordance with the present invention the possibilities of such clogging action are substantially eliminated by the provision of suitably shaped metallic rings 41 loosely surrounding the bolts 35 between the flanges 33 and the guide bar 14 and designed to comminute chips lodging in such areas and cause them to fall out under the vertical vibrating movement between the two parts. The metallic rings 41 are preferably hexagonal in cross-sectional shape as shown in Figures 5 and 6 but may alternatively be diamond shaped or square as shown by the rings 42 and 43 of Figures 7 and 8 or other desired shape which will provide opposite sharp edges disposed for action with the opposing surfaces of the flanges 33 and guide bar 14.

In the operation of the device, as a board or the like advances under the presser feet 11, the latter will move vertically against the action of the springs 39 and thus adjust themselves to any unevenness in the surface of the lumber. Vertical movement of the presser feet 11 is limited to the flanges 34 striking the lower edge surface of the guide bar 14. Thus if the unevenness of the lumber is such as to require a vertical movement of the presser feet greater than this, the entire mechanism will pivot about the pivot pins 17 and 18. Such pivoting movement is resisted by the weight of the chip breaker mechanism which is designed to correctly tension the springs 39 to exert the desired bearing pressure. Suitable weights or the like may be used to secure the desired tension of the springs 39. Thus upward vertical movement of the individual chip breakers is resisted in the first instance by the springs

39 and in the second instance by a part or all of the weight of the entire mechanism. Hence the possibility of damage to the mechanism by the uneven character of the stock being cut is substantially eliminated.

Furthermore, the possibility of clogging the machine by chips or the like is substantially diminished by a construction in which the parts likely to be clogged are substantially enclosed and shielded from the flying chips. And finally, stray chips which do lodge in the area between the flanges 33 and guide bar 14 are rapidly comminuted and discharged so as not to interfere with the proper functioning of the device.

Various modifications of the invention described and illustrated will most likely occur to those skilled in the art to which the invention relates and may be made without departing from the spirit of the invention, the scope of which is indicated in the attached claims.

I claim:

1. A chip breaker comprising a guide bar, a plurality of presser feet mounted on said guide bar, each of said presser feet having a recess therein for receiving said guide bar, the width of the guide bar being less than the length of the recess in each presser foot, aligned openings in said guide bar and each of said presser feet, pins disposed in said aligned openings for mounting said presser feet on the guide bar, a ring mounted on each of said pins between the guide bar and a wall of said recess, said ring being shaped to comminute chips and the like lodging in such area, and resilient means for urging each of the presser feet downwardly.

2. A chip breaker as set forth in claim 1 in which said ring is hexagonal in cross-sectional shape.

3. A chip breaker as set forth in claim 1 in which said ring is diamond shaped in cross-sectional shape.

4. A chip breaker as set forth in claim 1 in which said ring is square in cross-sectional shape.

5. A chip breaker comprising a guide bar, a plurality of presser feet mounted on said guide bar, each of said presser feet having a recess therein for receiving said guide bar, the width of the guide bar being less than the length of the recess in each presser foot, aligned openings in said guide bar and each of said presser feet, pins disposed in said aligned openings for mounting said presser feet on the guide bar, a chip displacing hard element interposed between the opposing surfaces of the upper wall of the recess of each of the presser feet and the upper side of the guide bar, said chip displacing elements embracing the pins and being mounted for movement relative to both said opposing surfaces and adapted to prevent accumulation of chips in the recess in the area of said opposing surfaces.

JAMES S. BALLANTINE.
